DESIGN FOR A HAND BAG CASE

Ossip J. Walinsky, New York, N. Y.

Application January 3, 1935, Serial No. 54,694

Term of patent 3½ years

To all whom it may concern:

Be it known that I, Ossip J. Walinsky, a citizen of the United States, and a resident of New York city, (Borough of Manhattan), in the county and State of New York, have invented a new, original, and ornamental Design for Handbag Cases, of which the following is a specification, reference being had to the accompanying drawing, forming a part thereof, and of which Figure 1 is an isometric perspective view, and Fig. 2 is an isometric perspective view of a handbag case

in open expanded position, showing my new design, the cover being shown partially broken away.

The dominant features of the design consist of a handbag having opposed gussets each having a rectangular outside panel, and triangular gusset portions at the sides thereof.

I claim:

The ornamental design for a handbag case substantially as shown and described.

OSSIP J. WALINSKY.
